UNITED STATES PATENT OFFICE

BENJAMIN B. COURTNEY, OF NEW ORLEANS, LOUISIANA

SURGICAL SADDLETTE

Application filed November 22, 1929. Serial No. 409,124.

The present invention relates to improvements in surgical saddlettes, and has for an object to provide a soft yielding surgical pile saddlette with means to support it in place.

Another object of the invention is to provide an improved saddlette for the treatment of piles in which the construction is simple and inexpensive and the use thereof 10 not irritable.

With the foregoing and other objects in view, the invention will be more fully described hereinafter, and will be more particularly pointed out in the claim appended 15 hereto.

In the drawings, wherein like symbols refer to like or corresponding parts throughout the several views,

Figure 1 is a fragmentary rear view of a 20 patient wearing the improved saddlette.

Figure 2 is a similar view from the front.

Figure 3 is an enlarged plan view of the 25 improved device with the belt partly open and the front straps separated from the belt.

Figure 4 is an enlarged side view, partly in section, of the improved pad.

Figure 5 is a longitudinal section there- 30 through, and

Figure 6 is a cross section taken on line 6-6 in Figure 4.

Referring more particularly to the drawings, 10 designates a belt from which depend a rear adjusting strap 11, and a pair 35 of front adjusting straps 12 and 13. These straps may be coupled to the belt, as by the use of a well-known form of garter fastening 14, whereby the straps may be removed from the belt. The straps themselves may 40 be adjusted as to length like the ordinary suspenders.

A rear tape 15 is sewed or otherwise connected to the rear strap 11, and a front tape has its ends sewed or otherwise connected to 45 the ends of the two front straps 12 and 13 which converge down from the belt. The legs of the front tape are indicated at 16 and 17. The intermediate portion of the front tape is looped and the free end of the 50 rear tape 15 is knotted, as at 18 in Figure

5, to the looped portion. After tying the knot the free terminal part 19 of the rear tape is inserted within the looped portion and sewed thereto.

A wad of loose cotton 20 is placed about 55 the knot 18 and adjacent portions of the tapes and forms with the chamois envelope 21 a pad. The chamois is cut in the form of an oval and stitched together at its longitudinal free ends after being made to 60 surround the body or wad of cotton. The tapes emerge through the unsecured ends of the envelope. Thread may first be wound about the cotton if desired to bind it to the 65 tapes.

In use the pad made of cotton, cloth tape and chamois will provide a soft, yielding 70 saddlette shaped to fit flush on the rectum, supporting the piles within the rectum, thereby holding same in place and keeping 75 them from protruding or becoming irritated; also preventing bleeding and itching and giving immediate relief to the patient.

To apply simply push the piles well into 75 the rectum, then adjust the saddlette pad to fit flush on the rectum and strap the belt tight around the waist. It will be noted that the soreness will be greatly relieved. After being worn from three to six days the 80 device may be removed as the piles will be greatly healed.

This supporter will be found not to cause 85 the patient any inconvenience or soreness whatever, and the patient may go about his duties without any uneasiness. The supporter is to be worn on the outside of the underclothing, and may be washed whenever necessary.

The device may be made in either cotton 90 or soft rubber or other materials.

It is obvious that various changes and 95 modifications may be made in the details of construction and design of the above specifically described embodiment of this invention without departing from the spirit thereof, such changes and modifications being restricted only by the scope of the following claim.

What is claimed is:

A saddlette comprising a belt, a rear 100

strap extending down from the rear of the belt, a rear tape depending from the rear strap, a pair of front straps connected with the belt to opposite sides of the front thereof and extending down in convergent relation, a front tape having its ends secured to the front straps and its intermediate portion looped, the rear tape being knotted about the looped portion and having a terminal part inserted within the looped portion and secured thereto, a wad of cotton placed about the joined portions of the tapes, and an oval envelope of chamois brought together about the cotton wad and stitched together to form an elongated pad tapering at both ends.
